(57) **CLAIM**

I claim the ornamental design for a two-piece adjustable forcible entry tool, as shown and described.

DESCRIPTION

FIG. 1 is a rear, side and top perspective view of the two-piece adjustable forcible entry tool disassembled into two parts;

FIG. 2 is a rear, side and top perspective view of the assembled two-piece adjustable forcible entry tool;

FIG. 3 is a top plan view of the assembled two-piece adjustable forcible entry tool;

FIG. 4 is a side elevation view of the assembled two-piece adjustable forcible entry tool;

FIG. 5 is a bottom view of the assembled two-piece adjustable forcible entry tool;

FIG. 6 is a rear view of the assembled two-piece adjustable forcible entry tool;

FIG. 7 is a front view of the assembled two-piece adjustable forcible entry tool;

FIG. 8 is a top plan view of the outer piece of the disassembled two-piece adjustable forcible entry tool;

FIG. 9 is a side elevation view thereof;

FIG. 10 is a bottom plan view thereof;

FIG. 11 is a top plan view of the inner piece of the disassembled two-piece adjustable forcible entry tool;

FIG. 12 is a side elevation view thereof; and,

FIG. 13 is a bottom view thereof.
